UNITED STATES PATENT OFFICE.

SARAH JANE SHIELS, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 15,497, dated October 28, 1884.

Application filed August 7, 1884. Term of patent 3½ years.

To whom it may concern:

Be it known that I, SARAH JANE SHIELS, of the city, county, and State of New York, have invented and produced a new and original Design for a Pattern of a Lady's Costume, (numbered 9,357;) and I do hereby declare that the engraved prints accompanying this specification convey to any one accustomed to using paper patterns a clear understanding of how a garment made up by the pattern will appear.

The design shows a round walking-skirt and an overdress. The skirt exhibits a lower front drapery that displays alternating plain and plaited panels, there being three plain and four plaited, and all of them extending nearly to the bottom of the skirt. The over-dress exhibits closely-fitted polonaise-fronts that shape short rounding paniers below the

closing and display draping plaits in their back edges, a closely-fitted basque-back, upon which appears to be draped a deep full back drapery that displays drapings at the center and at each side at the top, and also lower down at each side of the center, a standing collar, and coat-sleeves showing their wrists reversed in cuffs flaring at their back edges.

What I claim as my invention, and desire to secure by Letters Patent, is—

The design for a lady's costume, as shown in the engraved prints accompanying this specification.

SARAH JANE SHIELS.
